C. G. ANDERSON.
COMBINATION FAUCET.

APPLICATION FILED JAN. 30, 1917.

1,230,978.

Patented June 26, 1917.

UNITED STATES PATENT OFFICE.

CARL G. ANDERSON, OF DULUTH, MINNESOTA, ASSIGNOR OF ONE-HALF TO JOHN NORRÖRD, OF DULUTH, MINNESOTA.

COMBINATION-FAUCET.

1,230,978.

Specification of Letters Patent. Patented June 26, 1917.

Application filed January 30, 1917. Serial No. 145,381.

To all whom it may concern:

Be it known that I, CARL G. ANDERSON, a citizen of the United States, residing at Duluth, in the county of St. Louis and State 5 of Minnesota, have invented certain new and useful Improvements in Combination-Faucets, of which the following is a specification, reference being had therein to the accompanying drawing.

10 This invention relates to water faucets and has special reference to a combination faucet and drinking fountain adapted for use as a hot or cold water faucet or a drinking fountain, as desired.

15 The principal object is to produce such a device of the simplest possible construction and one easy of application and adjustment to suit circumstances.

Another object is to provide as sanitary 20 and practical a drinking fountain as possible.

Other objects and advantages will appear in the further description of the invention and illustrated in the accompanying drawings forming part of this application and in which like reference characters indicate like parts.

Figure 1 is a top plan view of the improved combination faucet.

30 Fig. 2 is a vertical central sectional view of same.

Figs. 3, 4 and 5 are horizontal sectional views through the valve showing the relative position of the parts in different adjustments of the valve.

The faucet is Y-shaped in plan view comprising the substantially cylindrical body portion 1, the two pipe connecting arms or branches 2 and 3, converging toward the

40 body portion and formed integral therewith, and the forwardly extending discharge member 4, which terminates in the downwardly curved nozzle 5 through which water is discharged as in the common faucet, said 45 forwardly extending portion is also formed integral with the body 1.

A drinking nozzle 6 is screw threadedly mounted within the upper wall of the member 4 and spaced a suitable distance from 50 the body 1 to admit of unobstructed access to the nozzle for drinking purposes and is attached in the manner described for the purpose of ready removal for cleaning or for removing entirely, and substituting

therefor a plug when the drinking nozzle 55 is not desired.

Each branch 2 and 3 terminates in a screw threaded portion 7 for connection with the hot and cold water supply pipes when the supply pipes occur in line therewith, but in the event of the pipes being opposed to each other, I provide auxiliary connecting means in the form of an internally screw threaded hole 8 formed in a suitable projecting boss 9 upon the side of 65 each branch.

When the direct end connections are employed, the lateral holes 8—8 will be plugged and when the faucet is connected by making use of the lateral holes, then the end 70 holes will be stopped by suitable caps or plugs, not shown, thus I have provided convenient means for attachment to various arrangements of water terminals.

The body 1 of the faucet is bored out from 75 the upper flat face 10 thereof downwardly forming a deep cylindrical aperture 11 therein into which is revolvably fitted the tapered plug or spigot valve 12 it having an operating stem 13 formed integral therewith. The valve 12 is somewhat less in height than the depth of the aperture in which it is supported by contacting the side walls thereof, it being normally slightly above the bottom of the aperture and considerably below the top. That portion of the side walls of the aperture above the upper end of the valve 12 is screw threaded and has similarly fitted therein the adjusting inverted U-shaped plug 14 which may 80 be tightened or loosened for proper working of the valve as is obvious, the lower edge of the plug impinging the upper circumferential edge of the valve.

To prevent the valve unduly seating with 95 in the aperture by revolving action thereof, I provide a metal spring washer, 15, placed within a suitable circular recess 16, the washer having an upwardly projecting resilient tongue 17 constantly impinging the bottom of the valve 12 and producing an upward thrust thereagainst.

Upon the upper end of the stem 13 is fixed in any desired manner as for example by the screw 18 and washer 19, a suitable 105 handle 20, which is employed in turning the valve.

That portion 21 of the shank intermediate

the handle 20 and the top of the plug 14 is squared and carries loosely fitted thereupon the indicator of pointer 22, the free downwardly curved end 23 of which extends to 5 a point adjacent the annular circumferential edge of the face 10 of the body 1. Upon the face 10 and in proper radial positions are suitable markings as indicated at 24 to 10 designate the position of the valve for accomplishing the results desired and in accordance with which the handle 20 may be intelligently adjusted.

The faucet has four separate water passages therein, two indicated by the numerals 25 and 26 for admitting cold and hot 15 water respectively and of identically the same size and shape, and two, 27 and 28, the former a discharge passage leading through the nozzle and the latter a smaller passage 20 directly above the former leading to the drinking fountain 6.

A small bypass 29 connects the passages 27 and 28 just beneath the fountain 6 and is designed to act as a drain therefor to prevent 25 any water remaining in the fountain after being used. This bypass is formed upon a slight inclination toward the nozzle 5 to prevent water unduly rushing upwardly therethrough when the nozzle 5 alone is dis- 30 charging.

The valve 12 has formed therein a peculiarly shaped transverse aperture designed to communicate with and control the flow of water through the passages in the faucet, 35 and which aperture has four discharge and receiving ports indicated at 30, 31, 32 and 33.

In forming the aperture in the valve as illustrated, three vertically disposed different shaped partition walls 34, 35 and 36 40 are formed about the aperture and which walls act as closures to the passage ways during the various adjustments of the valve. A radially and upwardly extending bypass 37 is formed in the valve 12 and provides 45 communication between the aperture in the valve and the fountain passage 28 when proper adjustment is made therefor as illustrated in Figs. 1, 2 and 3. In this adjustment the wall 35 acts as a closure to the hot 50 water passage 26 and the port 30 opens communication with the cold water passage 25 which will allow the water to pass freely through the aperture in the valve, the bypass 37 and passage 28 to the fountain 6. 55 The slight leak through the bypass 29 at such times will not materially interfere with the action of the drinking fountain and at

this adjustment of the valve the wall 36 closes communication between the aperture in the valve and the passage 27, as clearly 60 illustrated.

To close the faucet entirely, the handle 20 is brought to a neutral position between the two branches 2 and 3 with the indicator at "Stop." The position of valve in such instances is illustrated in Fig. 4, and in Fig. 5 the valve is illustrated as being open to discharge an equal amount of hot and cold water through the faucet nozzle 5.

It is not considered necessary to describe 70 in detail other adjustments or modifications thereof, and it is obvious that the proportions of hot or cold water in the discharge may be varied by slight movement of the valve.

It is evident that various changes in the details of construction and operation of the device may be resorted to without departing 75 from the spirit of the invention.

Having thus fully described my invention 80 what I claim and desire to secure by Letters Patent, is:

1. A combination faucet comprising a main discharge and a fountain discharge, a spigot within the faucet, a chamber within 85 the spigot having three different sized radially disposed openings, a discharge opening in the spigot communicating with the upper end of the chamber and adapted to communicate with the fountain discharge, and 90 means for adjusting the spigot to regulate the flow through either discharge, substantially as and for the purpose described.

2. The combination with a faucet as described, having a spigot valve therein, a 95 main discharge nozzle, a fountain nozzle and an indicator plate concentric with the valve, of a stem for the valve partly square in cross section, a threaded nut surrounding the stem and impinging the valve, a pointer 100 carried upon the squared portion of the stem and arched downwardly toward the indicator plate, means whereby the turning of the valve in accord with the indicator will direct either hot or cold water or both 105 through the main discharge nozzle, or cold water through the fountain nozzle substantially as set forth.

In testimony whereof I hereunto affix my signature in the presence of two witnesses. 110

CARL G. ANDERSON.
